UNITED STATES PATENT OFFICE.

JOHN A. CALDWELL, OF VANCOUVER, CANADA.

ELLIPSOGRAPH.

SPECIFICATION forming part of Letters Patent No. 530,822, dated December 11, 1894.

Application filed March 26, 1894. Serial No. 505,110. (No model.)

To all whom it may concern:

Be it known that I, JOHN A. CALDWELL, of Vancouver, British Columbia, Canada, have invented a new and Improved Ellipsograph, 5 of which the following is a full, clear, and exact description.

The invention relates to drawing instruments, and its object is to provide a new and improved ellipsograph, which is simple and 10 durable in construction, very effective in operation, and arranged to permit the operator to draw almost any kind of an ellipse.

The invention consists principally of a compass, a sleeve fitted to slide loosely on one of 15 the legs of the compass, and a rod held adjustable in the said sleeve and standing at right angles to the leg carrying the sleeve, the said rod supporting the pencil or pen.

The invention also consists of certain parts 20 and details, and combinations of the same, as will be hereinafter described and then pointed out in the claims.

Reference is to be had to the accompanying drawings, forming a part of this specification, 25 in which similar letters of reference indicate corresponding parts in all the figures.

Figure 1 is a perspective view of the improvement. Fig. 2 is a side elevation of an extension leg. Fig. 3 is an end elevation of 30 the pen holder. Fig. 4 is a side elevation of the same; and Fig. 5 is an enlarged sectional side elevation of a modified form of slide for the compass legs.

The improved ellipsograph is provided with 35 a compass having the legs A and B connected together by the pivot C in the usual manner. On the leg A of the compass is held adjustable a sleeve D adapted to be fastened in place on the leg by a set screw E, and on the said 40 sleeve is pivoted an arm F provided with a transversely-extending foot G having points adapted to engage the drawing board or other place on which the ellipse is to be drawn. The arm F with its foot G serves to adjust 45 and to hold the compass in a vertical position. The center point G' of the foot G is used to bring the legs A and B plumb, or to a true vertical position, that is when the legs A and point G' are in the same vertical plane.

50 On the leg B of the compass is fitted to slide loosely a sleeve H carrying a rod I adapted to be adjusted in the said sleeve,

and fastened in place after adjustment by a set screw H' screwing in the sleeve. This arm I stands at right angles to the leg B 55 and on one end thereof is held a holder J adapted to be fastened in place on the rod I by a set screw K. The holder J stands at right angles to the rod I and parallel to the leg B and is adapted to support a pencil L, 60 as shown in Fig. 1 or adapted to receive a pen holder illustrated in Figs. 3 and 4. This pen-holder is provided with a rod N held adjustable in the holder J and adapted to be fastened therein by a set-screw O, as shown 65 in Figs. 3 and 4.

On the lower end of the rod N is pivoted a support P carrying the pen Q and on the said support is held adjustable a pin R adapted to be fastened in place by a set screw R' 70 screwing in the support P, the said pin serving to hold the pen Q at all times in proper relative position to the paper or other article or material on which the ellipse is to be drawn. For drawing very large ellipses, I 75 prefer to make the slide H in the shape shown in Fig. 5, that is, form it with a bearing for a beam which is to take the place of the rod I, the beam being fastened in place by the set screw H'. Now, in order to draw an ellipse 80 the operator first adjusts the compass in such a manner that the point of the leg B is in the center of the ellipse to be drawn, with the other leg A having its point in the major axis of the ellipse as plainly indicated in Fig. 1. 85 The operator now turns the sleeve H and adjusts the rod I in the said sleeve until the pencil L or pen Q engages the minor axis of the ellipse at the outermost point of the said minor axis, and then the operator fastens 90 the rod I in place on the sleeve H and then swings the latter around and moves the leg A forward or backward on the major axis until the point of the pencil L or pen Q touches the outermost point of the ellipse on the major 95 axis. The operator then brings the legs A and B to a vertical position by engaging the foot G with the drawing board and with its center point on the major axis, and so by fastening the sleeve D holding the legs A and B vertical. The operator can now draw one- 100 half of the ellipse from one side of the minor axis to the other side thereof by turning the sleeve H on the leg B, the said sleeve moving

up and down on the leg according to the movement of the point of the pen or pencil on the paper. When this has been done the operator swings the leg A to the other side of the ellipse to again engage the major axis thereof and then the above described operation is repeated, that is, the other half of the ellipse is drawn in the manner described. Thus, it will be seen that by adjusting the legs A and B on the major axis and the rod I so as to bring the point of the pen or pencil on the extreme point on the minor axis of the ellipse, any desired ellipse may be drawn.

Having thus fully described my invention, I claim as new and desire to secure by Letters Patent—

1. An ellipsograph, comprising a compass, a sleeve fitted to slide loosely on one of the legs of the compass, and a rod held adjustable in the said sleeve and standing at right angles to the leg, the said rod carrying a pencil or pen-holder, substantially as shown and described.

2. An ellipsograph, comprising a compass, a device for adjusting to and holding the compass in a vertical position, a sleeve fitted to slide loosely on one of the legs of the compass, and a rod held adjustable in the said sleeve and adapted to be fastened thereto, the said rod standing at right angles to the leg carrying the said sleeve, the said rod also carrying a pencil or pen-holder, substantially as shown and described.

3. An ellipsograph, comprising a vertically-disposed compass, a sleeve fitted to slide loosely on one of the legs of the compass, a

rod held adjustable in the said sleeve and standing at right angles to the leg carrying the sleeve, and a holder held adjustable on the said rod and adapted to carry a pen or pencil, substantially as shown and described.

4. An ellipsograph, comprising a sleeve fitted to slide loosely on one of the legs of a compass, a rod held adjustable in the said sleeve and standing at right angles to the leg carrying the sleeve, and a holder held on the said rod and adapted to carry a pen or pencil, the said holder standing at right angles to the rod, substantially as shown and described.

5. An ellipsograph, comprising a sleeve fitted to slide loosely on one of the legs of the compass, a rod held adjustable in the said sleeve and standing at right angles to the leg carrying the sleeve, a holder held on the said rod, a second rod held adjustable in the said holder, and a pen support pivoted on the said second rod, substantially as shown and described.

6. An ellipsograph, comprising a sleeve fitted to slide loosely on one of the legs of the compass, a rod held adjustable in the said sleeve and standing at right angles to the leg carrying the sleeve, a holder held on the said rod, a second rod held adjustable in the said holder, a pen support pivoted on the said second rod, and a pin held adjustable on the pivoted support, substantially as shown and described.

JOHN A. CALDWELL.
